No. 882,347.

PATENTED MAR. 17. 1908.

H. O. RUGH,

COMPOSITE SIGNALING AND TELEPHONE SYSTEM.

APPLICATION FILED JUNE 14, 1906.

UNITED STATES PATENT OFFICE.

HARRY O. RUGH, OF SANDWICH, ILLINOIS.

COMPOSITE SIGNALING AND TELEPHONE SYSTEM.

No. 882,347.

Specification of Letters Patent. Patented March 17, 1908.

Application filed June 14, 1906. Serial No. 321,769.

To all whom it may concern:

Be it known that I, HARRY O. RUGH, a citizen of the United States, residing at Sandwich, in the county of Dekalb and State of Illinois, have invented a certain new and useful Improvement in Composite Signaling and Telephone Systems, of which the following is a full, clear, concise, and exact description, reference being had to the accompanying drawings, forming a part of this specification.

My invention relates to electrical systems for transmitting intelligence, and finds a most useful embodiment in composite signaling and telephone systems wherein the same line conductors act to convey telephonic and telegraphic currents. In the usual embodiment of my invention, a transmission line is employed to connect telegraph stations and telephonic outfits are connected between said telegraph stations. Where the telephonic outfits are connected with the transmission line, two sets of coils are employed, preferably each containing two coils preferably of the same ohmic resistance, one of each pair of coils possessing high impedance and the other preferably little or no impedance. The telephone receiver has its terminals connected or adapted for connection with the two sets of coils, the connection of one telephone receiver terminal being between the coils of one set or pair and the connection of the other telephone receiver being between the coils of the other set or pair. One impedance coil is interposed between one telephone receiver terminal and one telegraph station and the other impedance coil is interposed between the other telephone receiver terminal and the other telegraph station. One non-inductive resistance coil or connection is connected between one telephone receiver terminal and one telegraph station and the other non-inductive resistance coil or connection is connected between the other telephone receiver terminal and the other telegraph station. By this arrangement, the telegraphic currents find access through the two sets of coils in parallel. The impedance coils force said incoming telephonic currents through the non-inductive resistance coils or connections and the telephone receiver associated therewith. In short, it will be seen that I have provided at each telephone station a quadrilateral, two opposite sides of which contain the impedance

devices that I have described, while the other sides of the quadrilateral include means whereby the telephonic currents may be conveyed. These latter sides of the quadrilateral may, if it is desired, include impedance windings that are shunted by condensers, the condensers permitting the passage of telephonic currents while the impedance devices permit the passage of telegraphic currents.

I will explain my invention more fully by reference to the accompanying drawing, in which—

Figure 1 illustrates the preferred embodiment of my invention, and Fig. 2 illustrates another embodiment of the invention.

Like parts are indicated by similar characters of reference in both figures.

Transmission line 1 is shown as forming 75 telegraphic connection between two telegraph stations, A, B, and telephonic connection between telephone stations, C, D. I do not wish to be limited, however, to the number of stations that are connected by said 80 transmission conductor 1. At each telegraph station there is shown a part of the usual telegraphic apparatus, the part illustrated including a line relay 2, a telegraph key 3, together with connections that ground 85 the conductor 1 at the telegraph stations. There is shown included in series with the line at station A a closed circuit battery 4. At each telegraph station there is also indicated an impedance device 5 that serves to 90 prevent the passage of telephonic current to ground or telegraph stations beyond and also to prevent the abrupt rise and fall of the telegraphic impulses, whereby the tendency of the telegraphic currents to flow through the 95 telephonic instruments is reduced. At each telephone station there is indicated a grounded telephone switch-hook 6 that has an upper contact 7 forming a normally disconnected terminal of a local circuit that includes a 100 local battery 8, the primary 9 of an induction coil, a telephonic transmitter 10, and the switch-hook 6, this local circuit being closed when the receiver 11 is removed from said switch-hook. A circuit interrupter 12, preferably supplied in addition to the primary winding 9, is adapted for inclusion in a local circuit with the same battery 8, preferably while the receiver is upon its hook, a push button 13 being provided for this purpose, 105 which push button, when actuated, serves to bring the spring 14 into electrical connection 110

with the terminals 15, 16 and 17, whereby the winding of said circuit breaker 12 is brought into series with the primary winding 9 and the battery 8, occasioning impulses 5 that are by induction impressed upon the secondary 18 of the primary 9, this same secondary also serving to receive telephonic currents that are impressed thereon by the primary 9 when the button 13 is released and 10 the switch-hook is in an elevated position. The capacity of the winding 18 to transmit voice currents and signaling currents, constitutes one feature of my invention, though I do not wish to be limited in all embodiments of the invention to the character of signaling currents and the mechanism for producing the same herein set forth.

The signal device at each telephone station that is responsive to the signaling currents transmitted by the winding 18, desirably resides in a "howler" 19 of well known construction, this howler being normally grounded by way of the lower normal contact 20 of the switch-hook, so as to be 25 subject to incoming signaling currents.

Telephonic connections between telephone stations desirably include at each station a branch conductor 21 that contains a condenser 22, which condenser prevents the 30 passage of the telegraphic currents therethrough and permits the passage of telephonic currents to the corresponding telephone receiver when the switch-hook 6 is released.

At each telephone station there is provided a quadrilateral of connections, two opposite sides 23, 24 of which are adapted to 35 bar the passage of telephonic currents, while the remaining sides 25, 26 are adapted to 40 permit of the passage of telephonic currents. All the sides of the quadrilateral are adapted to permit of the passage of the telegraphic or other signaling currents that are to be transmitted between the stations A, B. For 45 these purposes, the sides 23, 24 preferably possess high impedance and the other two sides, 25, 26, possess conductivity for telephonic currents and telegraphic or signaling currents. In the embodiment of the invention shown in Fig. 1, the sides 25, 26 possess 50 only non-inductive resistance. In the form shown in Fig. 2, the sides 25, 26 may include impedance devices 27, 28 that permit passage of said telegraphic currents and condensers 55 29, 30 in shunt of the devices 27, 28, respectively, that permit the passage of telephonic currents. These condensers constitute non-inductive paths with respect to the telephonic currents. The sides 25, 26 of the 60 quadrilaterals also permit the passage of signaling currents occasioned by the operation of the buttons 13 and the circuit breakers 12.

With either system of connections shown in 65 Figs. 1 and 2, I connect one terminal 31 of

each telephone receiver between the adjacent sides 24, 26, and the other terminal 32 between the sides 23, 25.

Each telephone switch-hook desirably carries a conducting plate 33 that is adapted to 70 engage the two contacts shown above the same when the telephone switch is elevated upon the removal of the corresponding receiver, this arrangement being provided to prevent signaling currents occasioned upon 75 the operation of the devices 12, 13 from passing through the telephone receivers 11.

In operation, it will be seen that telegraphic or other suited signaling currents impressed upon the line and at either station 80 A or station B, finds a ready path over said conductor 1, through all of the sides 23, 24, 25, 26, this telegraphic or signaling current being smoothed by the impedance device 5 and prevented from finding access to the 85 telephonic apparatus by the condensers 22. Telephonic current impressed upon the line at station C, for example, finds circuit which may be traced from the ground permanently attached to the switch-hook, the upper contact 34, the condenser 22, the coil 18, the side 26 of the quadrilateral at station C, the receiver 11, the plate 33 and its then engaged contacts, the side 25 of said quadrilateral, to the station D, where it finds passage over the side 25 of the quadrilateral at 90 said latter station, the plate 33 at said latter station, the associate receiver 11, the side 26, the coil 18, the condenser 22, the contact 34 at station D, the switch-hook 6, to ground. 100 The voice currents impressed at station D upon the line 1 find a similar circuit, as will be apparent.

It will be seen that with reference to the telegraphic or other adaptable signaling currents impressed upon the conductor 1 at station A or B, there is no difference in potential between the terminals of the telephone receivers where they are connected with the quadrilateral, so that no such current impressed at said stations A or B can find passage to the telephone receivers 11, whereby telephonic communication may be conducted over the transmission line 1 at the same time signaling currents are passing over said conductor 1 between the stations A and B. 115

It will be seen that I have provided a composite signaling and telephone system including a transmission conductor, a plurality of signaling stations connected thereby, a plurality of telephone stations also connected thereby, apparatus for preventing passage of signaling currents from the former stations through the telephones at said telephone stations, a quadrilateral of connections at each 120 telephone station, the receiver circuit at each telephone station having one terminal connected between two of a pair of the sides of said quadrilateral and the other terminal connected between the two sides of the re- 125 130

maining pair of sides of said quadrilateral, the first pairs of sides of said quadrilateral each being connected in series with the transmission conductor and in parallel with each other, opposite sides of said quadrilateral possessing impedance to telephonic current and interposed between the associate telephone receiver circuit and the signaling stations, while the remaining sides of said quadrilateral include non-inductive resistance to permit the passage of telephonic currents, all of the sides of said quadrilateral affording passages for said signaling currents.

I do not wish to be understood as limiting myself to the location of stations A and C at different geometrical positions, nor to the locations of stations B and D at different geometrical locations, for stations A and C may be at one point, if desired, and stations B and D at another point, if desired.

The circuit afforded for the signaling currents occasioned upon the operation of the devices 12, 13 includes the ground permanently attached to a receiver switch-hook, 25 desirably the lower contact 20 at the station where this signaling current initiates, the conductor 35 at this station, the associate contacts 15, 16, the associate conductor 36, the condenser 22, the winding 18, the sides 30 23, 24, 25, 25 of both telephone stations, the winding 18 at the called telephone station, the condenser 22, the howler 12 at said latter station, the contact 20 and the grounded receiver switch-hook at the same station with 35 the latter howler. The howler 19 at the calling station is by the arrangement illustrated, preferably shunted or cut out of circuit and only the howler at the called station or stations is operated.

40 It will be observed that while the condensers 22 are in the telephonic circuit (when the receivers are removed from their switch-hooks), they are also included in shunt of the telegraphic keys, these shunts to the telegraphic keys not including the telephone receivers, whereby current impulses occasioned by the operation of the telegraphic keys are not impressed upon the telephone receivers, but find their way through the said 45 condensers, which by being included in shunts to the telegraphic keys which do not contain the telephone receivers, are able to shunt the said current impulses from the telephone receivers.

55 I have shown a composite telephone and telegraph system with but two telephone stations and without any intermediate telephone stations. I do not, therefore, limit myself to a composite system in which there 60 are no other telephone stations than those illustrated connected with the main transmission conductor, as it is obvious that other telephone stations with other circuit arrangements than those illustrated may be 65 connected with the transmission conductor.

without departing from my invention, and as such other telephone stations constitute no part of my present invention, I have not illustrated the same.

While I have herein shown and particularly described two embodiments of my invention, I do not wish to be limited to precise instrumentalities and circuit connections illustrated, but

Having thus described my invention, I claim as new and desire to secure by Letters-Patent:—

1. In a composite telegraph and telephone system, the combination with a transmission conductor affording passage for telegraphic current, a plurality of telegraph stations connected thereby, a plurality of telephone stations also connected thereby, said transmission conductor normally permanently extending to all of said telegraph and telephone stations, a quadrilateral of connections at each telephone station, the telephone receiver circuit at each telephone station having one terminal connected between two of a pair of the sides of said quadrilateral and the other terminal connected between the two sides of the remaining pair of sides of said quadrilateral, the said pairs of sides of said quadrilateral each being connected in series with the transmission conductor, the telegraph stations also being in serial relation with said quadrilateral, opposite sides of said quadrilateral possessing impedance to telephonic current and being interposed between the associate telephone receiver circuit and the telegraph stations while the remaining sides of said quadrilateral afford passage for voice currents, all of the sides of said quadrilateral affording passage for telegraph currents.

2. In a composite telegraph and telephone system, the combination with a transmission conductor affording passage for telegraphic current, a plurality of telegraph stations connected thereby, a plurality of telephone stations also connected thereby, said transmission conductor normally permanently extending to all of said telegraph and telephone stations, a quadrilateral of connections at each telephone station, the telephone receiver circuit at each telephone station having one terminal connected between two of a pair of the sides of said quadrilateral and the other terminal connected between the two sides of the remaining pair of sides of said quadrilateral, the said pairs of sides of said quadrilateral each being connected in series with the transmission conductor, the telegraph stations also being in serial relation with said quadrilateral, opposite sides of said quadrilateral possessing impedance to telephonic current and interposed between the associate telephone receiver circuit and the telegraph stations while the remaining sides of said quadrilateral afford passage for telegraph currents.

3. In a composite telegraph and telephone system, the combination with a transmission conductor affording passage for telegraphic current, a plurality of telegraph stations connected thereby, a plurality of telephone stations also connected thereby, said transmission conductor normally permanently extending to all of said telegraph and telephone stations, a quadrilateral of connections at each telephone station, the telephone receiver circuit at each telephone station having one terminal connected between two of a pair of the sides of said quadrilateral and the other terminal connected between the two sides of the remaining pair of sides of said quadrilateral, the said pairs of sides of said quadrilateral each being connected in series with the transmission conductor, the telegraph stations also being in serial relation with said quadrilateral, opposite sides of said quadrilateral possessing impedance to telephonic current and interposed between the associate telephone receiver circuit and the telegraph stations while the remaining sides of said quadrilateral afford passage for telegraph currents.

sage for voice currents, all of the sides of said quadrilateral affording passage for telegraph currents, conductors extending from the transmission conductor and completing the 5 telephonic circuit, and condensers in said conductors.

3. In a composite telegraph and telephone system, the combination with a transmission conductor affording passage for telegraphic 10 current, a plurality of telegraph stations connected thereby, a plurality of telephone stations also connected thereby, said transmission conductor normally permanently extending to all of said telegraph and telephone 15 stations, a quadrilateral of connections at each telephone station, the telephone receiver circuit at each telephone station having one terminal connected between two of a pair of the sides of said quadrilateral and the 20 other terminal connected between the two sides of the remaining pair of sides of said

quadrilateral, the said pairs of sides of said quadrilateral each being connected in series with the transmission conductor, the telegraph stations also being in serial relation 25 with said quadrilateral, opposite sides of said quadrilateral possessing impedance to telephonic current and interposed between the associate telephone receiver circuit and the telegraph stations while the remaining sides 30 of said quadrilateral afford passage for voice currents, all of the sides of said quadrilateral affording passage for telegraph currents, and conductors extending from the transmission conductor and completing the telephonic 35 circuit.

In witness whereof, I hereunto subscribe my name this 7th day of June A. D., 1906.

HARRY O. RUGH.
